UNITED STATES PATENT OFFICE.

HARRY NEGBAUR, OF NEW YORK, N. Y., ASSIGNOR TO E & J BASS, INCORPORATED, A CORPORATION OF NEW YORK.

DESIGN FOR A POCKET FLASK.

Application filed April 11, 1922. Serial No. 1,691. Term of patent 3½ years.

To all whom it may concern:

Be it known that I, HARRY NEGBAUR, a citizen of the United States, and a resident of the city, county, and State of New York, have invented a new, original, and ornamental Design for a Pocket Flask, of which the following is a specification, reference being had to the accompanying drawing, forming a part hereof.

Fig. 1 of the drawing shows a side elevation of the flask and Fig. 2 shows an end view of the same.

I claim:

The ornamental design for a pocket flask substantially as shown and described.

HARRY NEGBAUR.
